UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

MAGNETO-ELECTRIC GENERATOR.

Original application filed March 12, 1920, Serial No. 365,305. Divided and this application filed April 7, 1923. Serial No. 630,425.

To all whom it may concern:

Be it known that I, EDWARD B. NOWOSIELSKI, a citizen of the United States, residing at Bloomfield, in the county of Essex, State 5 of New Jersey, have invented certain new and useful Improvements in Magneto-Electric Generators, of which the following is a description, reference being had to the accompanying drawing and to the figures of 10 reference marked thereon.

This invention relates to electric generators, more particularly of the magneto type as are customarily used for ignition purposes in connection with internal combustion engines. This application is a division 15 of my application, Ser. No. 365,305, filed March 12, 1920, now Patent 1,477,843, issued December 18, 1923.

It is the principal object of my invention 20 to provide an electric generator of the ignition type which will be highly efficient in its operation, relatively simple in its construction and hence easy to manufacture. Some of the objections against armature 25 wound magnetos are pointed out in Mason Patent Reissue 14,373 dated October 2, 1917 and it is one of the objects of my invention to eliminate some of these objections.

In the electrical generator to be described 30 and claimed herein, the generating coil is stationary and is placed within the arch of the magnets and is completely enclosed by the magnets and end plates and, therefore, is fully protected from all injurious agents.

One of the principal objects of my invention is to provide a distributor block and 35 associated mechanism together with a circuit breaker, all completely enclosed within a simple housing or chamber so that these 40 parts are protected from dirt, water and other harmful agencies, yet the enclosures are so arranged that the parts may be readily gotten at by the removal of a single cover plate.

Another object of my invention is to provide attachment means to the breaker box which can be quickly adjusted for any position of the engine operated lever; that is to say, the advance lever on the breaker box 45 is of the universal type.

Other and further objects will be apparent to one skilled in the art after a study of the annexed drawings taken in connec-

tion with the specification. In the drawings:

Figure 1 is a side view of the electric generator with the magnet broken away to show the generating coil in working position.

Figure 2 is a right hand end view of Fig. 60 1, but with the cover plate removed.

Figure 3 is a view of the cover plate removed from the end plate shown in Fig. 2.

Figure 4 is a perspective view of the breaker box.

Figure 5 is a section on the line 5/5 of Fig. 2.

Figure 6 is a plan view of the coil heads showing the holes for the conductors leading from the coil.

Referring now to the details wherein like numbers refer to corresponding parts in the various views, 1 is a base or housing structure within which the rotor 2, shown in dotted lines, is positioned, being supported on bearings at either end, one of said bearings 6 being shown carried by the end plate 3, that is adapted to be fastened to the housing in any suitable manner such as by screws engaging holes in the end of 75 the frame. The other end plate is indicated at 5. Supported on the end plate 3 and preferably overlapping housing 1 is a supplemental plate 7, the upper end of which rests against the magnets 23 and is 80 also engaged by the cover plate 27 as will be clearly seen in Figure 1. The supplemental plate 7 is fastened to the end plate 3 by a screw 8 which is hollow and serves as an oil duct leading from the chamber 85 above the head of the screw down adjacent to the bearing 6. A lid 9 fastened to plate 7 covers the oil chamber leading to the screw 8. Carried on the top part of the housing 1 are two coil pole pieces 10 and 11 which are arranged longitudinally but spaced apart as indicated by 12. These 90 pole pieces are flat on top and of relatively large area to provide contact surfaces for the enlarged polar areas 13 and 14 of the core 15 which is U shaped and carries the generating coil 16 which preferably consists of a high and low tension winding such as is ordinarily used in a high tension generator. The polar projections 13 and 14 are 95 held in position on the poles 10 and 11 in

any suitable manner such as by clamps 17. By means of this construction the air gap between the pole pieces and the inductor elements remains undisturbed, while the coil 16 with its pole piece may be removed and easily replaced in position, leaving the magnetic circuit as it was before between the rotating elements and the coil pole pieces. The heads of the generator coil 16 are preferably made U shape so that the arms extend down around the polar areas 13 and 14 as indicated in Figure 1, in order to keep the laminations, of which core 15 is made, from spreading. These heads are preferably composite in character having one part 18 of magnetic metal which serves to prevent flux leakage and direct the flux from the pole-pieces 10 and 11 and polar areas 13 and 14 through the core 15 embraced by the coil 16, while an insulating member 19 is placed between 18 and the winding.

The description of the rotor and its co-acting pole pieces in the base 1 need not be herein described, since they form no part of the present invention and are fully described in my application, Serial No. 365,305 filed March 12, 1920. Furthermore the aforesaid parts may be varied over wide limits without effecting the subject matter of this application. It may be noted, however, that the base 1 has a recess 25 on either side to receive a projection in the cover plate 27 that is punched inwardly from said cover plate used to cover the magnets 23. Plate 27 is held in position by a clamping member which fits within the recess 25 so that when the cover plate is in the assembled position, there are no screws projecting therefrom, but a smooth finished surface is presented.

The end plate 5 is constructed with a chamber within the upper part of which a distributor block 20 is mounted, being held within the said chamber in any suitable manner as by screws 21. The distributor block shown is suitable for a four cylinder engine, the connections being made to the terminal posts of the block by contacts 22. The conductors 24 come out of the distributor block by way of grooves 26 and bushings 28 which are preferably of soft rubber set in plate 5. Carried in a suitable bearing (not shown) on the plate 5 is the usual distributor gear that is operated by driving pinion 29 carried on the shaft of the rotor. Associated with the distributor gear and the distributor block is a distributor finger 30, the same being held to the gear by screws 31 which also serve as one terminal of a safety gap, the other terminal of which is indicated at 32 and connection being made between the points 32 and electrode 33 having contacts with an electrical conductor 34 carried by terminal block 35 mounted on the

back of the plate 5. It is understood that the conductor 34 connects with a high tension winding of the coil 16 in any suitable manner. The distributor finger 30 carries a distributor brush 36 and distributes the current to the various contacts 22 all in a well known manner. The holder for the brush 36 has a projection 37 used for assisting in timing the generator with the engine.

Mounted in the lower part of the chamber 75 of plate 5 is the breaker box mechanism generally indicated by the numeral 38. An adjustable contact 39 is carried on the block 40 supported on the box 38 but insulated therefrom. The movable breaker arm 41, carrying the bumper 42 adapted to be engaged by the cam 43 carried on the end of the shaft 29, is pivoted to the member 38 in any suitable manner as by pivot pin 44. Breaker box 38 carries a spring 45 in the chamber 46. Spring 45 engages the breaker arm 41 at its extreme end and in line with the contact 39. Such an arrangement of controlling the spring for the movable breaker arm will allow the same to respond to high rotative speeds of the operating cam. It will be noted that while there is shown a two-lobe cam, the rotor used may be capable of producing four or more current impulses on the coil 16 for each revolution, 95 but the number of impulses is controlled by the type of cam used. Since the distributor indicated is for a four cylinder engine only two sparks per revolution are required, and hence a two-lobe cam is used. Conductor 47 100 is shown leading from the terminal 40 and this goes to a condenser carried within the chamber of plate 5, but since it is behind the distributor block 20 it is not shown. Another conductor 48 leads from the terminal block 40 to the coil 16, and another conductor 49 leads to a terminal post 50 that is wired to a control switch on the dash. The chamber of the end plate 5 is closed by a cover 51 having a rim 52 adapted to engage 110 the flange 53. The plate 51 carries an insulator 54 having a thrust member 55 adapted to engage the end of the conductor 33 to hold the distributor finger 30 in correct position. Spring 56 is used to give proper adjustable movement to member 55. On certain types of ignition generators where it is desired to bring out the high tension lead the thrust member 55 may take the form of a contact brush as will be well understood. 115

The lower part of cover 51 carries a stub shaft 57, on one end of which is fastened a lever 58, being clamped thereto in any suitable manner as by set screw 59, by which construction it will be understood that the 125 upper end of the lever 58 may be set in any desired position, to be engaged by the operating levers used for controlling the position of the spark; and since the lever 58 may be quickly adjusted to any position it is uni- 130

versal in its application. To the inner end of the stub shaft 51 is connected a bell crank lever 60, the end of which 61 is adapted to engage a slot 62 in the breaker box 38 to 5 rotate the same on the bearing surface 63 which co-operates with a suitable bearing surface on the plate 5. Movement of the breaker box 38 is limited by slot 64 engaging the stop pin (not shown) carried by 10 plate 5.

The cover plate 51 is preferably held to the cover plate 5 by quick detachable means such as springs 65 so that when these springs are actuated the whole of the plate 51 may 15 be removed and the entire distributor and circuit breaker revealed for inspection of operation, etc. The conductors leading to the distributor and circuit breaker are not disturbed and the machine can function 20 within plain sight of the observer. In the usual form of ignition generator the distributor block itself must be removed in order to get at the distributor finger, and of course this at once puts the machine out of 25 commission, while my construction is such that the entire block itself is covered up away from injurious agents but may be uncovered without disturbing its function, and since the tract for the distributor brush is 30 in plain sight when the cover plate 51 is removed, all parts with the possible exception of the condenser, are open for instant inspection.

While I have shown and described one 35 embodiment of my invention, I do not wish to be limited to the exact details shown and described, as it is understood that these may be varied to a great extent without departing from the spirit of my invention and 40 scope of my appended claims.

Having thus described my invention what I claim is:

1. In a magneto electric generator of the 45 class described, a base structure forming a housing carrying a rotor therein and having a pair of pole pieces fixed in tandem in the top of the housing and forming a part thereof, a coil structure carried on said pole pieces with means including said rotor for shifting magnetic flux through said coil, end plates attached to the opposite ends of said housing, one of said end plates carrying a distributor block on one side and a terminal connector on the other, a distributing finger 50 associated with said block, said connector carrying members electrically connecting the coil with said distributing finger, and a cover plate for enclosing the distributor block and finger within itself and said end plate.

2. A magneto electric generator of the 55 class described in which the generating coil is placed on the outside and on top of pole pieces forming in part a housing supporting the magnets and enclosing a rotor for 60

directing the flux through said coil and which husing is closed at its ends by end plates supporting the rotor, further characterized in that one of said end plates has a terminal connector on one side and a chamber 70 on the other side thereof, said chamber housing a distributor block at the top portion and a circuit breaker mechanism at the bottom portion, a distributor finger associated with the block, said terminal connector serving to electrically connect the coil with the distributing finger and a cover plate for closing the outer opening of said chamber. 75

3. A magneto generator of the class described in which the generating coil is placed on the outside and on top of pole pieces forming in part a housing supporting the magnets and enclosing a rotor for directing the flux through said coil and 80 which housing is closed at its ends by end plates supporting the rotor, further characterized in that one of said end plates has a terminal connector on one side and a chamber 85 on the other side thereof, said chamber housing a distributor block at the top portion and a circuit breaker mechanism at the bottom portion, a distributor finger associated with the block, said terminal connector serving to electrically connect the coil with 90 the distributing finger and a cover plate for closing the outer opening of said chamber, said cover plate carrying an adjustable 95 thrust member to engage the distributor finger, and a timing lever mechanism having a part to engage said breaker box and another part adapted to be engaged by an operating lever. 100

4. A magneto electric generator in which the generator coil is stationary and in which flux changes are produced through the core of said coil by a rotatable member supported on bearings between end plates and which carries inductors, coacting between magnet pole pieces and pole pieces associated with said coil, further characterized in that one of the end plates is formed with a 110 chamber on one side, within which a distributor block, distributor finger and circuit breaker mechanism for controlling the coil 115 are housed, a terminal connector on the other side of the plate for completing an electrical connection between the coil and the distributing finger and a single cover plate for closing the said chamber. 120

5. A magneto electric generator in which the generating coil is stationary and in which flux changes are produced through the core of said coil by a rotatable member supported on bearings between end plates and which carries inductors, coacting between magnet pole pieces and pole pieces associated with said coil, further characterized in that one of the end plates is formed with a chamber on one side, within which a dis- 125 130

tributor block, distributing finger and circuit breaker mechanism for controlling the coil are housed, a terminal connector on the other side of the plate for completing an 5 electrical connection between the coil and the distributing finger, and a single cover plate for closing the same chamber, said cover plate carrying a self adjusting member for engaging the distributing finger and 10 a timer lever mechanism consisting of a stub shaft with a bell crank lever on the inner end for engaging the circuit breaker mechanism and with an adjustable lever on the outer end to be engaged by an operating 15 lever as described.

6. A magneto electric generator in which the generating coil is stationary and housed within the arch of the magnets and in which flux changes are produced through the core 20 of said coil by a rotatable member supported on bearings between end plates and which

carries inductors, coacting between the magnet pole pieces and pole pieces associated with said coil, further characterized in that one of the end plates is formed with a chamber 25 on one side, within which a distributor block, distributor finger and circuit breaker mechanism for controlling the coil are housed, a terminal connector on the other side of the plate for completing an electrical connection between the coil and the distributing finger, a single cover plate for closing said chamber and further characterized in that the other end of the generator 30 has a supplemental plate fastened to its end 35 plate, said supplemental plate engaging the magnet for closing the coil within the arch thereof.

In testimony whereof, I affix my signature.

EDWARD B. NOWOSIELSKI.
